COIN AND SLUG SEPARATOR

Walter A. Tratsch and William Patzer,
Chicago, Ill.

Application August 8, 1938, Serial No. 223,585

1 Claim. (C.I. 194—100)

This invention relates to improvements in coin testing apparatus and has as its principal object the provision of a coin chute including a sweep movable into and out of the chute passage to dislodge certain coin elements, and blocking means arranged to coact with the sweep to block the passage in the region below the same substantially at the time the sweep is actuated.

Another object is the provision of operating mechanism for correlating the operation of the sweep and blocking means, said mechanism being further arranged for either manual or automatic operation.

Another object is the provision of means for actuating the operating mechanism responsive to deposit of a coin in the chute.

Other objects, advantages and economies peculiar to the invention reside in certain details of construction, form, and operation of the preferred embodiment illustrated in the accompanying drawings, which are described in the following specification.

In the drawings:

Fig. 1 is a side elevation of the improved chute with a portion of the discharge apron cut away;

Fig. 2 is an end elevation of the device of Fig. 1;

Fig. 3 is a perspective view of the chute of Fig. 1;

Fig. 4 is an elevational view of the interior of the chute with one of the cover plates removed;

Fig. 5 is a vertical section along line 5—5 of Fig. 4;

Fig. 6 is a fragmentary perspective of the interior of the chute and the sweep;

Fig. 7 is a fragmentary vertical section through the sweep mounting and operating means as viewed in the direction of line 7—7 of Fig. 4; while

Fig. 8 is a fragmentary perspective of the manual operating means.

In a preferred form of construction, the improved chute is made of two separable sections 10 and 11 (Figs. 2 and 5) consisting of a pair of cast plates of white metal or some other non-magnetic material with mold formations defining a chute passage including a coin entrance 12 (Fig. 4) at the top of the chute, and a plurality of coin exits 13 and 14 at the bottom of the passage. The coin exit 13 constitutes a reject opening, and the coin exit 14 constitutes an acceptance opening. Communicating downwardly at a relatively moderate inclination from the entrance 12, is an upper chute passage section 15 which communicates with a vertical passage sec-

tion 16. Arranged at the bottom of the vertical section 16 is a drop-out ledge 17 which is positioned opposite a drop-out opening 18 formed in the companion plate 10 so that a coin which descends onto the ledge 17 will gravitate sideways out of the chute through the drop-out opening 18.

Just above the ledge 17 is an oppositely inclined chute section 19 communicating from the vertical section into another but shorter vertical section 20 provided with a downwardly inclined ledge 21 terminating in the enlarged region above both of the exit openings 13 and 14.

Coin testing means is arranged in the region 15 of the main vertical section 16 and includes a rebound anvil 25 positioned to be engaged by coin elements of a predetermined character rolling down the incline 15 and operable to effect rebound of such elements safely over the ledge 17 and into the oppositely inclined section 19. A smaller anvil 26 is positioned at the beginning of the section 19 to absorb shock and prevent wear of the relatively softer material of which the chute is constructed, due to rebound of coins and also to contact by coins which are dropped vertically or nearly so, so as to strike the upper tip at the beginning of the section 19.

Coin elements which are spurious or made of relatively soft materials will not rebound properly from the anvil 25, but will drop onto the ledge 17 and pass out through the opening 18, and it is important to observe that coin elements leaving the upper section 15 must be possessed of a certain amount of kinetic energy in order to strike the anvil 25 properly, the vertical component of the force acting on the coin as it passes through the vertical section 16 toward the anvil being adequate to cause all but certain kinds of coins to miss the anvil or at least strike it in such manner that they will not rebound into the oppositely inclined section 19, but will move into the drop-out opening 18.

A further testing means includes an elongated permanent magnet 30 (Fig. 1) attached by means such as the bracket 31 in any convenient manner on the outside of the chute opposite the vertical section 16 with the long axis of the magnet substantially parallel to the vertical axis of the section 16, so that the field of the magnet occupies the major portion of the vertical section 16. As a result of this arrangement, all coin elements are obliged to pass through the field of the magnet 30 and eddy currents are set up in such coins with the result that there is some variation in the energy possessed by the

moving coin as it moves toward the anvil. However, genuine coin elements are affected so slightly that they strike the anvil properly and pass into the section 19 over the ledge 17, but spurious and improper coin elements undergo an energy change adequate to cause them to drop directly onto the ledge 17 or strike either of the anvils 25 or 26 in a manner which prevents their rebounding into the section 19, such coins thereafter being discharged through the drop-out opening 18.

Arranged below the middle inclined section 19 is a further testing means in the form of a pair of permanent magnets 35 and 36 mounted on the outside of the chute sections with their poles arranged to maintain a strong field across the lower inclined section 21 for the purpose of further affecting the dynamic properties of coin elements which are able to reach the lower section of the passage. Cooperable with the testing means 35-36 is a pair of selector elements 37 and 38 each provided with coin engaging points 37' and 38' and each adjustably mounted by the means 39 so as to position the points for engagement by coin elements moving off the lower tilted section 21 into the enlarged area above the exit openings 13 and 14. The arrangement is such that proper coin elements will pass between the selector elements 37 and 38 and move through the exit opening 14 into a suitable receptacle. Improper coin elements which have negotiated the upper passage sections will, however, engage one or the other of the selector points 37' or 38' and be deflected into the reject exit opening 13 as a result of the influence of the magnets 35 and 36.

In the event that magnetically attractable coin elements reach the section 21 and are arrested by the magnets 35 and 36, the coin passage would remain blocked, and in order to clear the chute of such coin elements there is provided a clearing means in the form of a sweep 40 (Figs. 4 and 5) pivotally mounted on pin means 41 seated in one of the chute sections 11 and rigid with a cam member 42 disposed on the outside of the section plate or casting (Fig. 3), it being pointed out that the pin 41 is also rigid with the sweep as a result of the provision of a shoulder 43 keying the pin to the sweep (Fig. 7), so that the sweep and the cam turn together.

The floor of the lower inclined chute section 21 is formed by a raised portion of the plate 11, and the sweep 40 is fitted closely against this raised portion for free movement in the chute when the plate sections are secured together, the upper end of the sweep having an offset portion 44 (Fig. 6) which overlies the floor of the section 21 so as to positively engage any coin elements resting in the latter. The sweep is normally disposed out of the chute passage in the full line position illustrated in Fig. 4 or in the dotted line position of Fig. 6, so that coin elements may freely traverse the chute passage. By rocking the cam 42, the sweep will be moved from its normal position into the dotted line position of Fig. 4 or the full line position of Fig. 6 to dislodge any coin elements resting in the section 21, such coin elements thereafter moving in the general direction of the selector elements 37 or 38, and because they will have started from rest in the section 21, they will in all probability be deflected by one or the other of the selector elements into the reject opening 13.

To assure that released coin elements shall not enter the acceptance opening 14, there is

provided a blocking mechanism including an arm 50 (Figs. 3 and 5) bowed between its ends as at 51 and mounted for rocking movement on the outside of the plate 11 by means of a headed pin 52 freely passed through the bowed portion thereof and anchored in the plate, there being a coil spring 53 about the pin normally urging the arm into position with its right-hand end portion 54 raised or drawn away from the side of the chute.

5 A blocking pin 55 (Fig. 5) is secured to the end portion 54 and projects through an opening in the plate 11 for positioning across the chute passage, as illustrated in Fig. 6, when the arm 50 is rocked against the compression of the spring 53 so as to cause the end portion 54 to approach the plate. When the pin 55 is thus projected into blocking position, all coin elements leaving the lower passage section 21 will be effectively blocked against movement into the discharge opening 14 so that all danger of acceptance of coin elements dislodged by the sweep, particularly, is removed.

Mechanism for simultaneously operating the sweep and blocking means includes the provision of a slide bar 60 mounted on pin means 61 and 62 on the plate 11 for vertical sliding movement, the bar having a longitudinal edge portion 63 offset to fit around the edge of the chute to assure uniform movement of the bar and also to provide for the operation by the bar of additional scavenging mechanism hereinafter to be described.

25 A pin 64 on the cam 42 fits into a slot 65 on an extension of the slide bar 60, so that reciprocation of the slide will effect oscillation of the cam, the latter having a cam edge 66 which bears against the inner surface portion of the rocker arm 50. When the slide bar is raised, the cam edge 66 will bear against the curved portion 67 of the rocker arm and project the blocking pin 55 into blocking position in the chute passage. The slide bar is provided with a normal spring 70 attached at one end to the pin 62, which in turn is secured to the chute plate 11, and attached at its opposite end to a pin 71 on the slide, thus urging the latter into a normally lowered position and retracting the cam 42 to permit normal positioning of the arm 50 by means of its spring 53, with the pin 55 likewise retracted and in ineffective position.

30 It will be recalled that the cam 42 is mounted on pin means 41 which is rigid with both the cam and the sweep 40 so that whenever the cam is moved, the sweep will likewise be moved, the arrangement being such that when the rocker arm 50 is rocked into blocking position, as viewed in Fig. 7, the sweep 40 will be in coin dislodging position as viewed in Fig. 6.

An additional testing and scavenging means includes the provision of a pivoted side wall section or gate 75 pivotally mounted as at 76 near the top of the chute so as to normally close an opening in the side wall 16 opposite the upper chute section 15 and a portion of the vertical chute section 16. Spring and pin means 84 normally urges the gate into fully lowered or closed position.

An elongated drop-out opening 77 is provided in the gate and extends collaterally with the floor of the upper slanting chute section 15 and has a width slightly less than the diameter of a desired coin element which the device is intended to accept, coin elements, which are undersized in respect to diameter, dropping through the

elongated opening 77 and into an exterior discharge chute 78 which descends along the outside of the plate 10 and terminates in a discharge opening 79 disposed alongside the reject opening 13, so that rejected coin elements of all kinds will be returned to the depositor.

Pivoted in a pair of horizontally spaced ears 80 is a feeler having a nose portion 81 disposed for projection into the chute passage at a predetermined point through the elongated drop-out opening 77 for the purpose of engaging perforate and similarly irregular coin elements to arrest the same. The feeler has an opposite end portion 82 offset for positioning opposite the upper polar end 83 of the elongated or "bar" magnet 30, which is mounted by the bracket 31 on the gate. By means of this arrangement, the offset portion 82 of the feeler is attracted to firmly, yet yieldingly, project the nose 81 into effective coin engaging position.

It will be apparent that various imperfect and spurious coin elements will be stopped by the feeler 81 and the bar magnet 30, and in order to clear the chute passage of elements thus arrested, means are provided for pivoting the gate into open position to dislodge coin elements engaged either with the finger 81 or arrested by the magnet 30, such dislodged coin elements dropping into the outside discharge chute 78 where they are finally disposed of.

Means for simultaneously moving the gate and the finger and blocking member includes the provision of a cam nose 85 (Fig. 3) on the offset edge portion 63 of the reciprocable slide bar 60, the nose being engageable with a lug 86 on the gate 15 such when the slide bar is raised, the cam 85 will rock the gate to open position.

An arrangement is provided for effecting automatic scavenging of the device to operate the gate, the sweep, and the blocking member automatically by the act of inserting a coin in the entrance opening of the chute. To this end, there is provided a dog leg lever 88 (Fig. 3) pivoted as at 89 on a side of the chute near the entrance opening 12 and having a roller 90 on the shorter arm 91 thereof positioned at the upper side of the vertical portion 12' of the coin entrance opening so that each time a coin is urged into the latter, it will ride against the roller 90 and a companion roller 92 pivoted at the opposite end of the opening portion 12' so as to rock the lever 88, the latter, in turn, being provided with roller means 93 at its lower end and which bears against an intermediate lever 94 pivoted on the side of the chute as at 95 and having an end portion underlying a pin 96 spaced above the pin 71 on the slide bar. Thus, when lever 88 is rocked by the insertion of a coin, lever 94 will be raised to raise the slide bar, open the gate, pivot the sweep, and rock the blocking member.

If desired, manual operating mechanism may be provided to replace the automatic means 88-90-94, such an arrangement being illustrated in part in Fig. 8, wherein there is a manually operated lever 100 pivoted as at 101 on the side 11 of the chute and having an end portion 102 engageable with a pin 103 on the bar 60, an opposite end portion of the lever being offset to provide a handle 104 which may be pressed down to raise the slide bar 60 and actuate the scavenging means in substantially the same manner as is effected through the automatic mechanism.

In operation, a coin element may be introduced

through the entrance portion 12' of the passage, from which it will descend into the upper section 15 to move past the elongated drop-out opening 77, if the coin element be of adequate diameter, and through the field of the magnet 30 in the vertical passage section 16, whereupon it will strike the anvil 25, and, assuming that the coin element be a proper one, that is, of predetermined physical characteristics including a certain hardness, into the intermediate and oppositely inclined section 19. It may be observed that the anvil 25 is preferably formed in a U shape, one leg of the U constituting the anvil proper which is disposed in a cut-out portion 21 in the casting at one side of the vertical section 16, so that the bight of the U fits around the adjoining edge portion of the plate with the opposite leg 28 of the U (Figs. 3, 4, 6) fitting against the outside of the same plate. Screws 29 are passed through the anvil portion of the U and through slightly elongated slots in the plate for engagement with the nuts 29' against the outside leg 28. By loosening the screws 29, the anvil may be raised or lowered slight amounts to effect proper rebound of the desired coin elements.

If the coin elements are of a relatively soft material, such as lead, type metal, and the like, or if they are underweight like cardboard and fiber discs, they will drop onto the ledge 17 at the bottom of the vertical section and fall out through the drop-out opening 18. On the other hand, if the rebound is adequate, the coin elements will continue down the section 19 and into the section 29 for movement through the field of the magnets 35 and 36, reactionary forces being set up in the metallic coin elements as a result of passage through this field, the genuine or desired coin elements reacting in a predetermined manner so as to pass between the selectors 37 and 38 for movement into the acceptance opening 17.

Should a magnetically attractive coin element be arrested by the magnets 35 and 36, the subsequent deposit of a coin element will effect reciprocation of the slide 60 and a resultant movement of the sweep 40 to dislodge such coin element, the same thereafter moving toward the blocking member 55 which at this time will also be disposed in blocking position as a result of the movement of the slide bar 60, so that the released coin must descend into the reject opening 13. Coin elements arrested by the feeler 81 or the vertically disposed bar magnet 30 will be released by the operation of the gate in the manner aforesaid.

The objects and advantages of the invention may be accomplished by other arrangements and forms of construction than that specifically described for purposes of illustration herein, and the appended claim is therefore not limited to any precise form of construction or operation, but is to be given the broadest interpretation consistent with the state of the art.

Having thus described our invention, what we claim as new and desire to protect by Letters Patent is:

In a coin testing device, the combination of means providing a coin passage terminating into coin acceptance and reject exits, test means communicating with the passage and adapted to arrest coins therein of predetermined character, an arm mounted to sweep across the face of said test means to dislodge a coin attracted thereto, a pin, adapted for movement through an opening

formed in said first means in a direction transversely of the passage, to block coins moving down the passage toward the acceptance exit, means pivotally supporting said arm for said sweeping movement, rockable means carried by 5 the first said means and supporting the pin for said transverse movement, means for moving said arm in sweeping action across the face of said

test means, an element of said arm-moving means being adapted to engage said rockable means to move said pin in said transverse direction simultaneously with the movement of said arm in sweeping action across the face of said test means.
